LINE-PUSHING MEANS FOR TYPE CASTING AND COMPOSING MACHINES.

1,271,206.

Specification of Letters Patent.

Patented July 2, 1918.

Application filed July 7, 1914. Serial No. 849,573.

To all whom it may concern:

Be it known that we, WILLIAM NICHOLAS, a subject of the King of Great Britain, residing at No. 222 West Twenty-third street, 5 in the city of New York, county and State of New York, and WILLIAM ACKERMAN, a citizen of the United States, residing in the village of Larchmont, in the county of Westchester, in said State, have invented new 10 and useful Improvements in Line-Pushing Means for Type Casting and Composing Machines, fully described and represented in the following specification and the accompanying drawings, forming a part of the 15 same.

Our invention relates to type setting and casting machines, having reference more particularly to the galley or type receiving mechanism thereof, and has for an object 20 to provide means for automatically stopping the machine when a line composed thereon either exceeds or falls short of the required length thereof.

Generally described, our invention comprises means for promptly shutting off the power by which the machine is driven when a line of improper length has been set and is being shoved into the galley, and in its preferred form employs a mechanism which 25 may be used to disconnect the driving mechanism, either to unclutch it from the source of power or in case of an electrically driven machine will operate to break the circuit by which the motor is driven. In whichever 30 form employed the disconnecting device may be actuated from two different points by a long line in its progress unto the galley, that is to say, at the time that the line is first pushed out of the assembling channel in 35 which it has been composed, when either a long or short line will cause the motor to stop, or later on by operation of a second detecting mechanism, a "tight" line, that is, one slightly longer than the normal or stand- 40 ard length, will likewise operate with the means employed to disconnect from the source of power and bring the machine to a standstill. The latter feature of our invention proves highly beneficial in providing an additional safeguard against a tight 45 line being crowded into the galley, which would prevent the matter being easily moved therein, as is almost constantly required in

handling type in galleys, or in locking up forms on the presses.

Having reference to the drawings illustrative of a preferred form of our invention, Figure 1 is a partial plan view of a type casting mechanism illustrating parts of our invention; Fig. 2 is an end view of the same, 60 and Fig. 3 is a partial sectional view of details shown in plan in Fig. 1.

Referring to the drawings: 1 represents the frame of a type casting machine of the class to which our improvements apply, such 65 for example as is described in our joint Patents Nos. 964,677 and 964,678, in which type are cast and fed into a galley mechanism, in connection with which we employ an adjustable galley side block 2, which, with the extension in the form of the side bar 10 supplies a support at one side for the type as it is being guided into the galley proper and a fixed wall at the opposite side.

Any of the familiar forms of printers' 75 galleys used in connection with type setting machines may be employed, which galley is clamped to the galley head of the machine in such manner that the type lines as they are composed are transferred therefrom into 80 the galley. We therefore use the essential features of the usual galley head to which the ordinary galley 5 is clamped, the fixed side wall 4 of which corresponding with one side of the galley and marks the position at 85 which the type are fed into the galley head by the type setting or composing machine, the other or opposite wall of the galley head being supported by the side block 2, to be adjustably located at an ascertained position 90 in accordance with the length of line to be held therein. In connection with the adjustable side wall we employ the usual form of line pusher except that in the preferred embodiment of our invention we use for this 95 purpose a head block or bar 6 which slides laterally upon the floor 8 of the galley head mechanism sufficiently to push a line of type transversely in the direction of the galley far enough to permit the formation of another line therein. The length of the head block 6 is determined by the width of column to be composed on the machine to which our improvement is applied, and may be operated in any convenient way, such for example, as is illustrated in the drawings, Fig.

1, mounted upon a sliding member 9 which is given sufficient movement to transfer the line laterally across the channel in which it is assembled into the galley head. The usual rule 7 is suitably held at the proper distance from the head block 6 parallel thereto to form the other wall of what may be termed the assembling channel, that in which the line is composed. The usual means are provided for withdrawing the rule either downwardly or otherwise, preceding the movement of the head block in pushing the line toward the galley.

10

Upon the head block 6 we provide a toothed sliding member 9 having a series of rectangular stops or teeth 9^a which measure one pica em from corresponding surfaces of adjacent teeth.

Pivots mounted upon a swivel post 10^a 20 is a stop finger 10 which has upon its under side a rectangular ledge 11 that is adapted to fit more or less snugly into the spaces between the stops 9^a which stop finger therefore crosses the channel in which the line of type is composed at a level near the body top of the type. The member 10 is adapted to swing upwardly upon its pivotal bearings on the post 10^a, which in turn is loosely held within its vertical bearing in the stationary portion of the sliding side block 2, so that the ledge 11 on the under side of the stop finger can readily be removed from one of the stop notches that is formed between the stops 9^a and replaced into any other desired.

30 35 When the stop finger 10 is thus connected with the toothed rack 9 which is loosely mounted upon the head block 6 the stop finger serves to mark the end of a line composed therein, the foremost character being in contact with the inner edge of the stop finger, which when thus located will measure lines of equal pica measurement. In order to increase the number of pica ems that may be set, it is necessary to place the block 2

40 45 at a position to correspond with the width of line required, and for this purpose a rod 12 extending laterally from the galley block 2 enters a horizontally split hole 13 suitably provided in an adjustable block 14 to receive the rod 12, a thumb screw 14^a being provided to clamp the rod 12 within said adjustable block. The block 14 is held upon the galley floor 8 by means of a shouldered screw 14^b through a slot in said block which

50 55 thus secures it firmly to the galley mechanism and by moving the block 12 to the extent permitted by the slot therein, that member may be adjusted to different positions, and likewise by reason of the rod connection in the block, the side block of the galley may be further adjusted laterally in accordance with the required line measurement to be held therein.

60 65 Thus by moving the side block 2 in a path parallel to the head block 6, the stop finger

10 may be carried into engagement with any one of the stops 9^a upon the toothed slide 9, as may be required in lines of even pica measurement. To further adjust the position of the stop finger 10 to lines varying in length by a fractional pica em, a further adjustment is provided by means of a horizontally mounted thumb screw 17, which is suitably mounted in brackets 16 in a second sliding member 15 on the head block 6, which slide 15 is held by means of a spiral spring 18 against a stop 19 on said head block so that as the screw is turned to the right or left the toothed sliding member 9 is accordingly moved to the full width of a pica em or any fraction thereof, as required.

70 75 Means having thus been provided for operably connecting the stop finger 10 through the toothed member 9 to sliding member 16 while the former in the manner described marks the end of the line, it will now be pointed out in what manner the shifting of the slide 15 may be employed to stop the operation of mechanism to cease at the proper time.

80 85 90 The line of type is being carried forward by positive means connected with the casting and setting mechanism so that whatever device is interposed at the fore front of the line as it is being assembled will be likewise impelled by positive means in the direction of the increasing length of the line. Hence in order to operate the slide 15 in the manner indicated by the line of type to stop the motor there has been provided upon the 100 slide 15 a rectangular projecting member 25, which when the head block 6 is in its normal position of rest extends toward the adjacent edge of the small table 21 at the end of the lever 20, which is pivotally mounted upon the frame 1 of the type casting machine.

95 105 110 Upon the table 21 is a recessed or socket-like portion 22 that is formed by the fixed stop 23 at one side and a stop 24 when the latter is in its normal or engaging position, as shown in Fig. 1, the stop 24 being pivotally attached to the fixed stop 23 so that if desired it can be thrown out of engagement with the projection member 25 when the latter is carried in the direction of the lever 20 by action of the head block 6, to which lever 20 the member 25 is fixedly attached. When therefore the pivoted stop 24 lies upon the table 21 in normal operable position, there is formed, between that member and the fixed stop 23, the recess 22 oppositely disposed to the member 25 on the block 3 and is constructed slightly in excess of the width of the member 25, so that when a line of type of proper length is being forced into the galley by operation of the head block 6, that member will safely enter the recessed portion 22, and the lever 20 will accordingly remain undisturbed thereby. But if the line 130

is long it will have carried the stop finger 10 when connected with the toothed member 9 into position to push the second slide 15 forward and the member 25 will thereby be 5 brought opposite the fixed stop 23 and when the line pusher 6 is operated the lever 20 will be engaged and rocked upon its pivotal bearing upon the frame of the machine.

The second slide 15 being normally held 10 against the stop 19 by action of the spring 18, it will ordinarily stand in a position to contact the swivel stop member 23, when the galley block is carried in the direction thereof to insert the line in the galley, so 15 that until brought to the position representing the required length of line by action of a line of proper measure having been fed in by operation of the plunger driving mechanism of the setting machines the extension 20 member 25 would strike the swivel member 23 and operate the shut-off lever 20.

The lever 20 when engaged by the rectangular extension of the slide 15 on the galley block will be rocked upon its pivot 25 and thereby rock the downwardly extending arm 26 attached thereto, which in turn will strike upon the end 31 of the latch 30 raising the forward end thereof out of engagement with a corresponding catch 33 30 upon a sliding rod 32 held horizontally in suitable bearings in the frame of the machine, which by action of the spring 34 upon the body thereof when thus released will carry the tapered rod 35 into position shown 35 in Fig. 2, which as will presently be explained, breaks the electric current by which the source of power is supplied to the type casting machine to which our improvement is attached.

40 The lever 20 is held in normal engaging position by means of a spring 27 having one end held against a stop projecting from the frame of the machine, the opposite end against a similar pin on the lever which 45 forces the lever 20 toward the rectangular projection 25 with which it coacts until the lever arm 26 is brought against the stop 28 likewise projecting from the frame of the machine. The latch piece 30 is similarly 50 held by its spring 30^a in engaging relationship with the slide 32 against the action of its spring 30^a.

The slide 32 is normally held in the position shown in Fig. 2 with its end 35 with- 55 drawn from the electric switch 36 having the two contacts 37, to one of which the current is led from the source of power, the other being electrically connected with a motor, so that when the end 35 is thrust in 60 the direction of the switch 36, its tapered end comes into electric connection with the contacts 37 to complete the circuit by which the motor is driven.

When the rod 32 has been once allowed by 65 action of its spring to break the circuit it

may be again brought into position to restore the connection by means of a small hand lever 38 pivotally attached to the frame of the machine, one arm of which is adapted to contact the end of the rod 30 projecting through the frame of the machine as shown in Fig. 2.

70 Thus far the mechanism has been explained for preventing long and short lines from being carried into the galley by means of the stop 25 contacting either side of a corresponding recess 22 which it has been pointed out is slightly in excess of the width of said member 25. It is not practicable in operating a mechanism of this class to construct the recess so as to exactly fit upon the projection 25, a slight leeway being allowed at either end to compensate for natural springiness of a line of composition in order to prevent the machine being shut off at 80 times when the error in the length of a line is comparatively unimportant. It has been found in practice that there is greater inconvenience entailed by lines slightly in excess of the standard length over those 85 falling short by a correspondingly slight amount, in that the longer lines form what is known to printers as tight lines, which interfere with proper locking up of forms. Therefore a supplementary mechanism is 90 employed for detecting tight lines and automatically shutting off the power by operation of the mechanism already described, which we will next refer to more in detail.

95 The side block 2 has upon its inner surface a longitudinal sliding wall 40, which has upon its upper surface a pin 41, which is adapted to engage with an angular cam surface 42 by means of which when the sliding member 40 moves in the direction of 100 type being fed into the galley, impinges on the cam surface 42, causing the stop finger 10 to be pivotally rocked in a horizontal plane upon its swivel base 9 in the same manner as the progress of the line in the 105 galley operates upon its finger to cause the projecting member 25 to be carried into engaging relationship with the fixed stop 23 upon the end of the lever 21. The sliding wall 40 is normally held in position by 110 means of a spring pawl 43 on the top of the block within one end of which is held by action of its spring 44 against a laterally inclined surface 45, which tends to hold the sliding wall 40 in its normal position. The 115 spring action will ordinarily be sufficient to return the wall 40 to such normal position after having performed its function on being engaged by a tight line but to enable the operator to assist the operation thereof 120 a thumb piece has been provided in the form of a short arm 46 on the pawl 43, which upon being pressed by the finger may be made to return the parts to their normal 125 position, under conditions in which the pin 130

will fail to act. This precaution is often found necessary in order to allow a line to pass into the galley which while having been set of a length sufficient to operate the 5 shut-off mechanism is still thought proper to be passed along into the galley.

The mechanism thus far described does not operate to disconnect the motor until the galley head block moves the line into the 10 galley. It is however desirable in those cases in which the line is too long to be received by the galley mechanism, to have the motor stopped before the line pushing mechanism operates. To this end a second arm 15 26^a is added to the bell lever 26 upon the outer end of which is an upwardly extending link 50 which is adapted to slide in guides 51 upon the frame of the machine, having upon its upper end a lug 52, having 20 on its under side a straight cam surface 53 formed at an incline of about 45 degrees (see Fig. 3). The lug 52 overhangs the forward end of the sliding member 15 upon which is a correspondingly inclined cam surface 54 within the path of which is interposed said lug 52 as said slide 15 moves longitudinally of the block 3 upon which it is 25 slidably mounted. As the incline is thus forced under the lug 52 the latter is elevated 30 when its under surface is engaged thereby, causing the vertical link 50 to raise the arm 26^a of the bell lever, thereby depressing the arm 26 upon the latch 30 which is holding the horizontal contact rod 32 into engagement 35 with the terminals 37 of the motor, which thereby releases the same to break the circuit in the same manner as when the upper arm of the bell lever 20 has been engaged as described above, for the purpose of disconnecting the motor. 40

Having described our invention, what we claim is:

1. In a type casting and composing machine, means for stopping the operations 45 thereof during line delivery when a line of type not of normal length has been composed thereon, said means comprising line controlled mechanism for disconnecting the source of power of said machine and mechanical line actuating means comprising mechanism operated by a line of abnormal length to set in position circuit breaking mechanism to be operated by the line delivering mechanism. 50

2. In a type casting and composing machine, means comprising line controlled mechanism for disconnecting the source of power of said machine, said line controlled means comprising a stop pivotally attached 55 to a swivel post operably mounted upon a

side block of the line receiving or galley mechanism, and a slide actuated thereby having a tongue member laterally projecting therefrom; a lever actuated contact slide; means comprising a socket piece on said lever adapted to register with said tongue member for rocking said lever to actuate said contact breaking slide. 65

3. In a type casting and composing machine, line delivering mechanism comprising 70 a line pushing block and a slidable member thereon, one end of which slidable member adapted to operate mechanism for disconnecting the source of the driving power of said machine; adjustable means for slidably 75 actuating said member upon said line pushing block comprising a longitudinal series of rectangular teeth; and a stop member pivotally attached to a swivel post, said stop member normally disposed across the path of 80 a line being composed therein.

4. In a type casting and composing machine, a line delivering mechanism comprising a line pushing block and a slidable member thereon; means for adjustably attaching 85 to said slidable member a line engaging stop pivotally attached to a swivel support and adapted to slide said member upon said block; means for moving said slidable member by said line engaging stop when engaged 90 by the end of an advancing line of type composed theron; and means attached to said slidable member for disconnecting the source of power of said machine as it is slid longitudinally upon said block by action of said 95 stop member.

5. In a type casting and composing machine, a line delivering mechanism comprising a line pushing block and a slidable member thereon; means for adjustably attaching 100 to said slidable member a line engaging stop pivotally attached to a swivel support and adapted to engage said slidable member; said stop being actuated by direct contact of the line as it advances while being composed 105 therein and means comprising a second slidable member having a pin adapted to contact a cam portion on said line engaging stop adapted to vibrate said stop horizontally to 110 actuate said slidable member on the line pushing block when said second slide is engaged by frictional contact with a tight line.

In testimony whereof, we have hereunto set our hands in the presence of two subscribing witnesses.

WILLIAM NICHOLAS.
WILLIAM ACKERMAN.
